CIRCUIT BREAKER

Hiller D. Dorfman, Beaver, Pa., assignor to Westinghouse Electric Corporation, East Pittsburgh, Pa., a corporation of Pennsylvania

Application October 18, 1950, Serial No. 190,825

15 Claims. (Cl. 200—88)

1

This invention relates to circuit breakers and more particularly to circuit breakers of the type used for controlling lighting and moderate power distribution circuits.

An object of the invention is to provide a circuit breaker with means for effecting opening of the breaker upon a failure of the insulation in electrical equipment.

Another object of the invention is to provide a circuit breaker supplied with, or for supplying, electrical current through trailing cables with means for causing opening of the breaker upon a breakdown of the cable.

Another object of the invention is to provide a circuit breaker having ground current trip means for causing opening of the breaker in response to failure of the insulation with protective means for protecting the trip means upon repeated attempts to close the breaker while a persistent ground fault exists.

The novel features that are considered characteristic of the invention are set forth in particular in the appended claims. The invention itself, however, both as to structure and operation, together with additional objects and advantages thereof, will be best understood from the following detailed description thereof when read in conjunction with the accompanying drawings.

In said drawings:

Fig. 1 is a vertical longitudinal sectional view of a circuit-breaker embodying the invention, the breaker being shown in the closed position;

Fig. 2 is a sectional view on an enlarged scale of the overcurrent trip device;

Fig. 3 is a sectional view on an enlarged scale of the ground-fault trip device;

Fig. 4 is a diagrammatic view of the circuit breaker and the connecting cable; and

Fig. 5 is a plan view of the circuit breaker with the cover removed.

Referring to Fig. 1 of the drawings, the two pole breaker is mounted in an enclosing casing for a three pole breaker. The circuit breaker comprises generally a base 7 and a cover 9, both of molded insulating material, operating mechanism indicated generally at 11; an over-current trip device indicated generally at 13, and a ground fault trip device indicated generally at 15 (Fig. 3). The casing formed by the base 7 and cover 9 is divided into three longitudinal compartments by partition walls 14 (only one being shown) and matching partition walls 16. Stationary contacts 18 and cooperating movable contacts are disposed in at least two of the compartments and, together with the corresponding terminals and con-

necting conductors, form the two poles of the breaker. Each pole of the breaker is provided with end terminals 17 disposed in suitable openings in the base at each end thereof.

5 The respective stationary contacts 18, one for each pole, are each mounted on the lower end of a conductor 21 secured to the base 7. At its upper end the conductor 21 is electrically connected to the respective terminal 17.

10 The movable contact structures for the two poles are the same, for which reason only one will be described. The movable contact 20 for the pole disposed in the center compartment is secured to a contact arm 27 which is loosely supported on a channel-shaped switch arm 29 (Fig. 1). The two channel-shaped switch arms are rigidly fastened for unitary movement by means of a tie bar 31 which extends across both poles of the breaker. The channel-shaped switch arm in the center compartment is pivotally mounted by means of a pivot pin 32 supported in a U-shaped frame 25 secured to the base 7.

15 The movable contact structure, comprising the switch arm 29, the tie bar 31 and the contact arm 27 for both poles of the breaker, is adapted to be operated to open position and to closed position by the common operating mechanism 11. This mechanism may comprise a carrier 33 pivotally mounted by means of a pivot pin 35 on the U-shaped frame 25, a pair of toggle links 37 and 39 interconnecting the carrier 33 and the switch arm 29 in the center compartment, a U-shaped operating lever 41, overcenter springs 43 connecting the operating lever 41 to the knee pivot pin 45 of the toggle 37—39 and an insulating operating handle 47 for the operating lever 41.

20 The two legs of the operating lever 41 are disposed adjacent the inner sides of the legs of the U-shaped frame member 25 and are pivotally supported on pins 49 projecting inwardly from the frame members. The operating handle 47 projects through a slot 51 in the cover 9 and has an arcuate protective portion 53 and side plates 55 integral with the portions 53. The side plates of the handle straddle the frame 25 and are secured to the two legs of the operating lever 41. The carrier 33 is normally held in latched position, as shown in Fig. 1, by a latch 58 (Fig. 2) of the trip device 13 which engages the free end of the center.

25 With the parts in the closed position, as shown in Fig. 1, the contacts are manually opened by clockwise movement of the operating handle 47 to the opposite end of the slot 51. During this movement the overcenter springs 43 will snap

overcenter below the center line of the toggle link 37 causing collapse of the toggle 37-39 and opening movement of the movable contact structure. The contacts are closed by movement of the handle 47 in the opposite direction to the position shown in Fig. 1. This movement causes the overcenter springs 43 to move overcenter in the opposite direction and move the toggle 37-39 to the in-toggle position to simultaneously close all of the contact means.

The circuit breaker is tripped open automatically in response to overload currents occurring in either pole of the breaker, by operation of the trip device 13 (Fig. 2). The trip device includes a bimetal element 61 and an electromagnetic trip means indicated generally at 63 for at least one of the two poles of the breaker. Each bimetal element 61 is rigidly secured to one turn of an energizing winding 65 for the electromagnet 63 of the corresponding pole. One end of the winding 65 is connected by means of a conductor 67 to the lower terminal 17 and the other end of the winding is secured to a conductor 69 which is connected by a flexible conductor 71 to the movable contact arm for the corresponding pole. In addition to energizing the magnet 63, the winding 65 serves as a heater for the bimetal element 61.

Each of the magnetic trip devices 63 comprises a U-shaped magnet yoke 73 secured to an insulating support member 75 suitably mounted on the base 7. A center core member 77 is secured to the portion of the U-shaped yoke which lies adjacent the support 75 and extends downwardly therefrom through the energizing winding 65. An armature 79 is pivotally supported on one leg of the U-shaped magnet yoke 73 and is biased to unattracted position by means of a spring 81. A common trip bar 83 of molded insulating material extends across the trip devices of the two poles and is operable by either of the bimetal elements 61 and also by the electromagnetic trip means 63 for either pole of the breaker. The trip bar 83 is pivotally mounted on a pair of brackets 85 (only one being shown) extending downwardly from the support member 75 and is biased in a counterclockwise direction to latching position by means of a spring 87. The trip bar 83 is provided with a projection 89 for each pole suitably secured thereto and having one end disposed to be engaged by the armature 79 for its associated pole. Also secured to the trip bar 83 is an arm 91 for each pole having adjusting screws 93 mounted in the free ends thereof to be engaged by the associated bimetal element 61.

The latch member 58 which engages and normally restrains the carrier in operative position is pivotally and slidably mounted on a pin 95 supported in the legs of a yoke-shaped bracket 97 mounted on the support member 75. A spring 99 biases the latch 58 in a counterclockwise direction. The latch member 58 is normally prevented from moving in a clockwise or unlatching direction by engagement of the portion 101 thereof with a latching projection 103 on the trip bar.

The trip device functions to trip the breaker after a time delay in response to overload currents below a predetermined value of, for instance, 1000% of normal rated current and instantaneously in response to overload currents above the predetermined value, or in response to short circuit currents.

The bimetal element 61 is heated by the coil

65 on which it is mounted, and when heated a predetermined amount in response to persistent low overload currents, deflects downwardly engaging and actuating the trip bar in unlatching direction to release the latch member 58. Release of the latch member 58 effects release of the carrier 33 which is then rotated counterclockwise carrying the center line of the toggle link 37 overcenter above the line of action of the overcenter spring 43 whereupon the springs 43 cause collapse of the toggle 37-39 and opening movement of the switch member 29.

Release of the carrier 33 is also effected by operation of the electromagnetic means 63 in response to overload currents above 1000% of normal, or a short circuit. Upon the occurrence of a heavy overload or a short circuit current, the electromagnet of the affected pole is energized an amount sufficient to attract the armature 79 causing the armature to engage the projection 89 and instantaneously actuate the trip bar 83 to effect release of the carrier 33 and opening of the contacts.

Before the contacts can be closed following an automatic tripping operation, it is necessary to reset and relatch the carrier 33. This is accomplished by moving the handle 47 clockwise as far as it will go. During this movement of the handle a projection 105 on the operating lever 41 engages the carrier and moves it therewith until the end of the carrier wipes by the latch 58. This action also effects relatching of the latch members 58 with the projection 103 on the trip bar 83. The contacts can now be closed in the previously described manner by upward movement of the handle to the position shown in Fig. 1.

The circuit breaker may be tripped open response to a loss of voltage by means of an undervoltage trip device which is shown schematically at 107 in Figs. 4 and 5. The undervoltage trip device is located in the right hand compartment of the three compartment housing (Fig. 5) and may be of any suitable well known type, preferably of the type disclosed in copending application Serial No. 187,555, filed September 29, 1950, by T. W. Slobodnik and assigned to the assignee of the instant application. Such undervoltage trip devices usually comprise a voltage coil and an armature that is held in attracted position so long as the coil is energized by normal voltage but which is released and caused to engage and actuate the trip means upon a predetermined loss of voltage.

The undervoltage trip device 107 (Fig. 5) comprises a voltage coil 108, a U-shaped magnet yoke 110 mounted by means of a bracket 112 and a block 114 on the insulating support member 75, an armature 116 and a trip rod 118 secured to the armature 116. The armature 116 is biased by means of a spring (not shown) in a direction to cause the rod 118 to engage and actuate the trip bar 83 but is normally held in attracted position by energization of the coil 108 in response to normal voltage. Upon a predetermined loss of voltage, the armature 116 is released and the spring (not shown) functions to actuate the trip rod 118 and effect tripping of the breaker.

The armature 116 is reset by movement of the operating handle 47 to the reset position to reset the breaker mechanism. When the handle 47 is moved to the reset position the side plate 53 thereof engages an arm 120 secured to a shaft 122 rotatably mounted in the block 114 and rotates the shaft in a direction to cause an arm 124

secured to the other end of the shaft to engage and move the armature 116 to its attracted position. If normal voltage has been restored to the coil 108, the magnet will be energized and hold the armature in its attracted position and the breaker may be closed. If, however, the normal voltage has not been restored then upon movement of the handle 47 away from the reset position, the spring (not shown) will again actuate the trip rod 118 to trip the breaker.

For certain applications, it is desirable that the circuit breaker shall open the circuit immediately upon the occurrence of a breakdown of the insulation of the equipment, or in the event that the insulation deteriorates to such a point that leakage currents to the frame reach a predetermined value. This protection is provided by means of a ground fault trip device, indicated generally at 15 (Figs. 3 and 4), connected in a circuit connecting the frame of the protected equipment to ground.

The ground fault trip device 15 is located in the left hand compartment in the three compartment housing (Fig. 5) and may comprise an electromagnet indicated generally at 109 (Fig. 3) having an energizing coil 111 connected in series relation in the ground circuit. One end of the coil 111 is supported on a rigid conductor 113 which is connected by means of a flexible conductor to the contact arm 27 in the left hand compartment of the housing. The ground circuit extends through the stationary and movable contacts 18 and 20 in the left hand compartment and is connected to an upper terminal 115 shown schematically at the right hand side in Fig. 4. The other end of the coil 111 is connected by means of a flexible conductor 117 to the free end of a bimetal element 119 having its other end rigidly supported on a conductor 121 which, in turn, is connected to a terminal 123, shown schematically in Fig. 4. A U-shaped magnet yoke 125, similar to the magnet yoke 73 of the overcurrent trip device, is mounted on the support member 75 and has an armature 127 pivotally mounted on one of the legs thereof. The magnet yoke 125 (Figs. 3 and 5) has a center core member 129 similar to the center core member 129 similar to the center core member 77 for the other poles extending through the center of the coil 111 and a spring 131 compressed between the armature 127 and the center core member 129 biases the armature to unattracted position. A member 132 rigidly secured to the trip bar 83 is disposed to be engaged by the armature 127 upon operation thereof to actuate the trip bar.

The circuit breaker is preferably provided with a switch arm and contact means to open the ground circuit upon opening of the breaker in order to protect two pieces of ungrounded electrical equipment, the frames of which may come into contact with each other. However, the switch arm may be omitted from the ground circuit and the ground current trip device may be connected directly to the upper terminal 115 by a solid conductor.

The electromagnet 109 is designed to trip the breaker in response to a ground fault current of predetermined magnitude of, for instance, 10 amperes. Upon the occurrence of a ground fault, the electromagnet 109 (Fig. 3) is energized thereby and attracts the armature 127 to actuate the trip bar 83 and effect instantaneous tripping of the breaker.

While the circuit breaker may be used to protect any ungrounded electrical equipment, it has

been shown schematically in Fig. 4 as applied to an ungrounded mobile piece of equipment which utilizes a trailing cable to supply power thereto from a supply line. Referring to Fig. 4, a distribution breaker A is connected to a supply line 133. The distribution breaker is connected by means of a cable indicated schematically at 135 to a load breaker B which, in turn, is connected to the electrical equipment indicated at M. The main power supply line extends through the main contacts 18-20 and the overcurrent trip device 13 of each of the two poles of the distribution breaker A, wires 137 in the cable 135 and through the main contacts 18-20 and overcurrent trip devices 13 of each of the two poles of the load breaker to the equipment M. The undervoltage trip device 107 for the distribution breaker A is connected across the main power lines and through the cable 135 by wires 139, the circuit being completed by a conductor 141 across the connecting terminals on the load breaker B. The ground circuit is connected from the frame of the equipment M serially through the ground fault trip device 15 of load breaker B, wire 143 in cable 135, the ground fault trip device 15 of distribution breaker A to ground.

When the breaker is opened either manually or automatically in response to an overload, undervoltage or ground fault condition, the ground circuit is also opened by the switch arm and contacts in the left hand compartment. If the breaker is not provided with separable contacts in the ground circuit, this circuit is not opened but remains connected as previously described. The ground fault current will, however, be interrupted by opening of the main contacts 18-20. Should the breaker be closed before the cause of the ground fault current has been eliminated, current will again flow through the ground circuit. This can result in a dangerous condition since the frame of the equipment becomes charged to a dangerous potential above ground potential. It has been found that when a piece of portable equipment becomes disabled due to a ground fault, workmen attempt to inch the disabled equipment to an out-of-the-way position by repeatedly closing the circuit breaker while the ground fault condition exists. Such repeated closing of the breaker under this condition may cause the ground fault trip coil 111 to become excessively heated and burn out.

It is the function of the bimetal element 119 (Figs. 3 and 4) to prevent repeated reclosures of the circuit breaker against a persistent ground fault current. The bimetal element 119 does not operate in response to ordinary ground fault currents since the coil 111 effects tripping of the breaker before the bimetal element is heated sufficiently to trip the breaker. However, after the breaker is closed a few times against a ground fault current, the bimetal element 119 becomes heated by the excessive current flowing therethrough and by the heat from the coil. When heated a predetermined amount, the bimetal element 119 deflects downwardly (Fig. 3) and engages an adjusting screw 145 carried by a projecting member 147 secured to the trip bar 83 and actuates the trip bar to the unlatching position. The bimetal element 119 will hold the trip bar in unlatching position until the bimetal cools at which time the breaker can be reset and reclosed in the previously described manner. If, at this time, the ground fault has not been corrected, the coil 111 will again be energized and immediately trip the breaker open again.

Having described the invention in accordance with the patent statutes, it is to be understood that various changes and modifications may be made in the structural details without departing from some of the essential features of the invention.

I claim as my invention:

1. A ground current limiting circuit breaker for controlling an electrically operated device having an ungrounded frame comprising a plurality of sets of relatively movable main contacts, operating means therefor including means for manually opening and closing said sets of main contacts, overcurrent trip means responsive to overload currents traversing said sets of main contacts to effect automatic opening of said sets of main contacts, terminals on said breaker for connecting said breaker in a circuit connecting the frame of said electrically operated device to ground, one of said sets of said main contacts being connected in a circuit between said terminals, an electromagnetic trip device responsive to abnormal current flowing through said one set of contacts to effect opening of said sets of main contacts and opening of said circuit between said terminals, and thermally responsive means heated in response to said abnormal current flowing through said one set of contacts upon repeated closing of said sets of main contacts and operable when heated a predetermined amount to prevent further closing of said sets of main contacts and said circuit through said one set of contacts until said thermally responsive means has cooled.

2. A circuit breaker for controlling an electrically operated device having an ungrounded frame comprising a plurality of sets of relatively movable contacts, operating means for said sets of contacts including an operating handle for manually opening and closing said sets of contacts, a trip member operable to cause an automatic opening operation of said operating means, trip means operable in response to predetermined abnormal current conditions in the circuit controlled by said breaker to actuate said trip member, terminals on said breaker for connecting said breaker in a circuit connecting the frame of said electrically operated device to ground, one of said sets of contacts being connected in a circuit between said terminals, electromagnetic trip means comprising an energizing winding energized in response to excessive current flowing through said one set of contacts and an armature operable upon energization of said winding in response to excessive current of predetermined magnitude to instantaneously actuate said trip member, and a thermally responsive element connected to be heated in response to excessive current flowing through said one set of contacts upon repeated closing of said sets of contacts with excessive current in said circuit and operable when heated a predetermined amount to engage and actuate said trip member to thereby limit the number of closing operations.

3. A circuit breaker for controlling an electrical translating device having an ungrounded frame comprising a plurality of sets of relatively movable contacts, operating means releasable to effect automatic opening of said sets of contacts, said operating means including an operating handle movable to an "on" position and to an "off" position for manually opening and closing said sets of contacts, a trip bar operable to release said operating means, a trip device responsive to abnormal conditions in the circuit controlled by the breaker to actuate said trip bar, terminals on

the breaker for a circuit connecting the frame of said translating device to ground, one set of said contacts being connected in a circuit in said breaker between said terminals, electromagnetic trip means comprising an energizing coil energized in response to predetermined currents occurring in said circuit between said terminals, an armature operable upon energization of said coil to actuate said trip bar, and a bimetal element disposed to be heated in response to said currents in the circuit between said terminals upon repeated closure of said contacts and operable when heated a predetermined amount to engage and actuate said trip bar and hold said trip bar in actuated position for a predetermined time.

4. A circuit breaker for controlling an electrical translating device having an ungrounded frame comprising a plurality of sets of separable contacts, operating means releasable to effect automatic opening of said sets of separable contacts, said operating means including an operating handle movable to an "on" position and to an "off" position for manually opening and closing said sets of separable contacts, a trip bar normally restraining said operating means and operable to release said operating means, a trip device responsive to abnormal conditions in the circuit controlled by said breaker to actuate said trip bar, terminals on the breaker for connecting said breaker in a circuit connecting the frame of said electrical translating device to ground, one set of said separable contacts being connected in a circuit in said breaker between said terminals, electromagnetic trip means comprising a coil energized in response to currents of predetermined value flowing through said one set of contacts, an armature operable upon energization of said coil to actuate said trip bar and cause automatic opening of said sets of separable contacts, and a current traversed bimetal element heated in response to excessive currents flowing through said one set of separable contacts and disposed adjacent to said coil to be heated in part thereby, and said bimetal element when heated a predetermined amount upon repeated closing of said contacts bending in a direction to engage and actuate said trip bar and hold said trip bar in actuated position until said bimetal element cools.

5. A circuit breaker for controlling an electrically operated device having an ungrounded frame comprising separable contact means, operating means including an operating handle for manually opening and closing said separable contact means, said operating means being releasable to effect automatic opening of said separable contact means, a trip member normally restraining said operating means in operative position and movable to a position to release said operating means, trip means responsive to overload currents in the circuit controlled by said breaker for moving said trip member to releasing position, terminals on said breaker for a circuit connecting the frame of said electrically operated device to ground, a circuit in said breaker between said terminals controlled by said separable contact means, a trip device responsive to excessive currents in said circuit between said terminals to move said trip member to releasing position, and a current traversed bimetal element heated by excessive currents in said circuit between said terminals only upon repeated closure of said contacts following operation of said trip device in response to excessive currents flowing in said circuit between said terminals,

said bimetal element when heated a predetermined amount bending in a direction to engage and move said trip member to releasing position and holding said trip member in releasing position for a predetermined time.

6. In a circuit breaker having a plurality of current paths therethrough, a trip unit comprising a single trip bar operable to effect automatic opening of said breaker, a first trip device calibrated to be responsive to overload currents above normal rated current of the unit in one of said current paths for actuating said trip bar, a second trip device comprising an electromagnet calibrated to actuate said trip bar in response to excessive currents of predetermined value in another of said current paths, and a thermal device heated by excessive currents in said other current path upon closely successive repeated operations of said second trip device and operable when heated a predetermined amount to engage and actuate said trip bar to tripped position and hold said trip bar in tripped position until said thermal device has cooled.

7. In a circuit breaker having a plurality of current paths therethrough, a trip unit comprising a single trip bar operable to effect automatic opening of said breaker, a first trip device calibrated to be responsive to currents above normal rated current of the unit in one of said current paths for actuating said trip bar, a second trip device comprising an electromagnet calibrated to actuate said trip bar in response to currents of predetermined value in another of said current paths, and a bimetal element disposed to be heated by excessive current in said other current path upon closely successive repeated operations of said second trip device to engage and actuate said trip bar to tripping position and hold said trip bar in tripping position until said bimetal element has cooled.

8. In a circuit breaker having a plurality of current paths therethrough, a trip unit comprising two trip devices for actuating a single trip bar to effect automatic opening of said breaker, one of said trip devices being calibrated to be responsive to currents above the normal rated current for said unit in at least one of said current paths, the other of said trip devices comprising an electromagnet calibrated to be responsive to predetermined currents below the normal rated current for said unit in another of said current paths, and a thermal device heated by excessive currents in said other current path in response to closely successive repeated operations of said other trip device to engage and actuate said trip bar and hold said trip bar in actuated position until said thermal device has cooled.

9. In a circuit breaker having a plurality of current paths therethrough, a trip unit comprising two trip devices for actuating a single trip bar to effect automatic opening of said breaker, one of said trip devices being calibrated to be responsive to currents above the normal rated current for said unit in one of said current paths, the other of said trip devices comprising an electromagnet calibrated to be responsive to predetermined currents below the normal rated current for said unit in another of said current paths, and a bimetal element connected to be traversed by currents in said other current path, said bimetal element being heated by excessive currents in said other current path in response to closely successive repeated operations of said other trip device and operable when heated a predetermined amount to engage and move said trip bar to tripped posi-

tion and to hold said trip bar in tripped position until said bimetal element has cooled.

10. A multi-pole circuit breaker having a movable switch arm in one or more of each of two poles and operating means therefor, a trip bar movable to a tripping position to effect opening of said breaker, an overload trip device in one or more of the circuits through said one or more switch arms calibrated to be responsive to overload currents of relatively high value for moving said trip bar to tripping position, an additional circuit in said circuit breaker having a magnetic overcurrent trip device connected in said additional circuit and traversed by the entire current flow in said additional circuit at all times and calibrated to be responsive to currents of relatively low value in said additional circuit for moving said trip bar to tripping position, and a thermal device heated in response to currents in said additional circuit and operative only following an operation of the magnetic overcurrent trip device in said additional circuit to engage and move said trip bar to tripping position.

11. A multi-pole circuit breaker having a movable switch arm in one or more of each of two poles, a trip bar movable to a tripping position to effect opening of said breaker, an overlead current responsive trip device in one or more of each of said two poles operative to move said trip bar to tripping position, an additional circuit in said breaker having an additional movable switch arm therein, a common operating mechanism for said switch arms, a current responsive trip device in said additional circuit comprising an electromagnet connected in said additional circuit and traversed by the entire current flow in said additional circuit at all times, said electromagnet being operative in response to currents of predetermined value in said additional circuit to move said trip bar to tripping position, and a bimetal element connected to be traversed by current in said additional circuit, said bimetal being disposed to be heated by the current in said additional circuit and operative only when heated during two or more operations of said electromagnet to engage and move said trip bar to tripping position.

12. A two-pole circuit breaker comprising an enclosing casing having therein three compartments positioned side by side, a trip bar movable to a tripping position to cause automatic opening of said breaker, a movable switch arm in one or more of each of two of said compartments, operating means for said switch arms, an overload trip device in one or more of said two of said compartments calibrated to be responsive to currents of predetermined value and operative to move said trip bar to tripping position, an additional circuit in the third of said compartments, a trip device in said additional circuit comprising an electromagnet connected in said additional circuit and traversed at all times by the entire current flowing in said additional circuit, said electromagnet being calibrated to be responsive to currents below said predetermined value and operative to move said trip bar to tripping position, and a bimetal element heated by current in said additional circuit upon closely successive repeated operations of said electromagnet and operative when heated a predetermined amount to engage and move said trip bar to tripping position and to hold said trip bar in tripping position until said bimetal has cooled.

13. A two-pole circuit breaker comprising an

enclosing housing having therein three compartments positioned side by side, a single trip bar movable to a tripping position to effect opening of said breaker, a movable switch arm in one or more of two of said compartments, an overload trip device in one or more of the circuits through said switch arms for moving said trip bar to tripping position, an additional switch arm in the third of said compartments, operating means for said switch arms, an electromagnetic trip device connected in the circuit through the additional switch arm and traversed at all times by the entire current flowing in the circuit through said additional switch arm in said third compartment, said electromagnetic trip device being responsive to current in the circuit through said additional switch arm for moving said trip bar to tripping position, and a bimetal element in said third compartment connected to be traversed by the current in the circuit through said additional switch arm, said bimetal element being heated only upon closely successive repeated operations of said electromagnetic trip device to an amount sufficient to engage and move said trip bar to tripping position, and said bimetal element then holding said trip bar in tripping position until said bimetal element has cooled.

14. A two-pole circuit breaker comprising an enclosing casing having therein three compartments, a single trip bar movable to a tripping position to effect automatic opening of said breaker, a movable switch arm in each of said three compartments, operating means for said switch arms, two overload trip devices in the circuits through two of said switch arms calibrated to move said trip bar to tripping position in response to overload currents above a predetermined value in the circuits through said two movable switch arms, an electromagnetic trip device connected in series in the circuit through the switch arm in the third of said compartments and traversed at all times by the entire current flow in the circuit through the switch arm in said third compartment, said electromagnetic trip device being calibrated to move said trip bar to tripping position in response to currents below said predetermined value, and a bimetal element heated in part by excessive cur-

rents flowing in the circuit through the switch arm in said third compartment and disposed to be heated in part by the heat of said electromagnet, said electromagnet being operative only when heated during a plurality of closely successive repeated operations of said electromagnet to engage and move said trip bar to tripping position.

15. A two-pole circuit breaker comprising an enclosing casing having therein three compartments, a single trip bar movable to a tripping position to effect automatic opening of said breaker, a movable switch arm in each of said three compartments, operating means for said switch arms, two overload trip devices in the circuits through two of said switch arms calibrated to move said trip bar to tripping position in response to overload currents above a predetermined value in the circuits through said two movable switch arms, an electromagnetic trip device connected in series in the circuit through the switch arm in the third of said compartments and traversed at all times by the entire current flow in the circuit through the switch arm in said third compartment, said electromagnetic trip device being calibrated to move said trip bar to tripping position in response to currents below said predetermined value, and a thermal device in the circuit through the said switch arm in the third compartment calibrated to cause movement of said trip bar to tripping position in response to two or more closely successive operations of said electromagnetic trip device.
